DESIGN FOR AN ELECTRICAL CONNECTING PLUG HOUSING

Alexander R. Nagy, New York, N. Y.

Application April 26, 1946, Serial No. 128,967

Term of patent 7 years

(Cl. D26—1)

To all whom it may concern:

Be it known that I, Alexander R. Nagy, a citizen of the United States of America, residing at New York, in the county and State of New York, have invented a new, original, and ornamental Design for an Electrical Connecting Plug Housing, of which the following is a specification, reference being had to the accompanying drawings, forming a part thereof.

Figure 1 is a perspective view of an electrical connecting plug housing showing my design;

Figure 2 is a view in vertical section taken along the line 2—2 of Figure 1; and

Figure 3 is a bottom plan view of the housing shown in Figure 1.

The dotted line showing in Fig. 1 is for illustrative purposes only.

I claim:

The ornamental design for an electrical connecting plug housing, substantially as shown and described.

ALEXANDER R. NAGY.
